CLAIM

We claim the ornamental design for a cable guide, substantially as shown and described.

DESCRIPTION

FIG. 1 is a top isometric view of a cable guide.

FIG. 2 is a left side elevation view of the cable guide of FIG. 1.

FIG. 3 is a right side elevation view of the cable guide of FIG. 1.

FIG. 4 is an enlarged fragmentary view of a portion of the left side elevation view of the cable guide of FIG. 1 as indicated in FIG. 2.

FIG. 5 is an enlarged fragmentary view of a portion of the right side elevation view of the cable guide of FIG. 1 as indicated in FIG. 3.

FIG. 6 is an enlarged front elevation view of the cable guide of FIG. 1.

FIG. 7 is an enlarged rear elevation view of the cable guide of FIG. 1.

FIG. 8 is a top plan view of the cable guide of FIG. 1.

FIG. 9 is a bottom plan view of the cable guide of FIG. 1.

FIG. 10 is a top isometric view of the cable guide of FIG. 1.

FIG. 11 is a bottom isometric view of the cable guide of FIG. 1.

FIG. 12 is an enlarged fragmentary top isometric view of a portion of the rear of the cable guide of FIG. 1 as indicated in FIG. 10.

FIG. 13 is an enlarged fragmentary top isometric view of a portion of the front of the cable guide of FIG. 1 as indicated in FIG. 10.

FIG. 14 is an enlarged fragmentary bottom isometric view of a portion of the rear of the cable guide of FIG. 1 as indicated in FIG. 11; and,

FIG. 15 is an enlarged fragmentary bottom isometric view of a portion of the front of the cable guide of FIG. 1 as indicated in FIG. 11.

The broken lines shown represent unclaimed subject matter and form no part of the claimed design. The dash dot broken lines shown in FIGS. 2, 3, 10, and 11 are used to identify the portions of the design enlarged in FIGS. 4, 5, and 12-15 as indicated and form no part of the claim.
